UNITED STATES PATENT OFFICE.

JACOB KAST, OF EAST BOSTON, MASSACHUSETTS, ASSIGNOR TO ROBERT A. HAMMOND, OF SANDWICH, MASSACHUSETTS.

FLAT WIRE BELT OR ROPE.

No. 841,154.

Specification of Letters Patent.

Patented Jan. 15, 1907.

Application filed January 17, 1906. Serial No. 296,493.

To all whom it may concern:

Be it known that I, JACOB KAST, a citizen of the United States, residing at East Boston, in the county of Suffolk and State of Massachusetts, have invented new and useful Improvements in Flat Wire Belts or Ropes, of which the following is a specification.

The object of this invention is to provide a flat belt or rope which may be used for any of the purposes for which rope or belting is now used, and which shall possess great strength and frictional capacity against slipping, and which shall be very durable and strong in its construction and adapted to be used without injury or deterioration in places where it is liable to become wet.

The object of the invention is, further, to provide a flat belt which is very flexible and convenient to handle and which, while possessing the characteristic of great frictional capacity, is so constructed that the different strands of which it is composed are firmly held with relation one to the other, so that there is no rubbing or chafing of one strand upon another, which would result in the wearing out of said strands and causing the belt to become broken.

The invention consists in a flat belt or rope composed of a series of strands extending longitudinally thereof and two strands interwoven with said longitudinal strands which extend across said belt and across each other alternately in opposite directions, these transverse or cross strands serving to hold the longitudinal strands firmly fixed in relation one to the other. Said longitudinal strands are divided into two sets, and all of the strands of one of said sets extend across and outside said cross-strands on one face of said belt and all of the strands of the other of said sets extend across and outside said cross-strands on the other face of said rope or belt.

While my improved belt may be formed of any kind of fibrous material, such as hemp, I prefer to construct the same of wire strands, each of said strands being composed of a series of wires twisted tightly together, and said strands being each covered with a twisted strand of hemp or other fibrous material which is "served" around the same to form an outer elastic covering therefor.

In the drawings my improved flat belt or rope is illustrated as formed of strands constructed as hereinbefore described, both the

longitudinal strands and the transverse strands being of the same construction. This forms the strongest and most durable construction for a belt of the character set forth; but it would be possible to use a belt constructed with longitudinal strands of wire covered with fibrous material served around the same, while the transverse or locking strands could be made of hemp or other fibrous material without departing from the spirit of my invention.

Referring to the drawings, Figure 1 is a front elevation of a portion of a flat rope embodying my invention. Fig. 2 is a longitudinal section, partly in elevation, taken on line 2 2 of Fig. 1. Fig. 3 is a transverse section, partly in elevation, taken on line 3 3 of Fig. 1.

Like numerals refer to like parts throughout the several views of the drawings.

In the drawings, 5 is a piece of flat wire rope or belt consisting of a plurality of strands 6 6 6 7 7, extending longitudinally of said belt, each of said strands being composed of a plurality of wires 8, which are twisted tightly together, after which the wire strand so formed is firmly and closely wound or wrapped in one direction by serving it with a single twisted strand 9 of hemp or other suitable fibrous material, preferably tarred, to prevent rust or corrosion, which forms a soft or elastic outer covering or cushion for the said wire strand and also serves to protect the wires from wear. By the construction hereinbefore described the friction or rubbing of the wires 8 of one strand against those of another is entirely avoided, and the individual wires are also prevented from rubbing against the covering and wearing the same, thus greatly increasing the durability and life of the belt.

The longitudinal strands 6 6 and 7 7 are interwoven with two strands 10 11, which alternately cross the belt 5 in opposite directions, and at each crossing of the belt said transverse strands 10 and 11 also cross over or under each other respectively, thus firmly uniting and tying the longitudinal strands 6 6 and 7 7 together and preventing the same from spreading laterally, the resulting structure being a very strong durable resilient structure which possesses great frictional capacity and durability and which is also practically impervious to water, so that the

same may be used out of doors or in connection with shipping in any of the various forms in which such a device would be used without injury or deterioration.

5 Having thus described my invention, what I claim, and desire by Letters Patent to secure, is—

1. A flat rope or belt consisting of two sets of longitudinal strands and two strands interwoven with said longitudinal strands and crossing said belt and each other alternately in opposite directions, all of the strands of one of said sets extending across and outside said cross-strands on one face of said rope and all of the strands of the other of said sets extending across and outside said cross-strands on the other face of said rope.

15 2. A flat rope or belt consisting of two sets of longitudinal strands and two strands in-

terwoven with said longitudinal strands and 20 crossing said rope and each other alternately in opposite directions, all of the strands of one of said sets extending across and outside said cross-strands on one face of said rope and all of the strands of the other of said sets extending 25 across and outside said cross-strands on the other face of said rope, all of the strands of each of said sets respectively, crossing from one face to the other of said rope between each crossing of said cross-strands.

30 In testimony whereof I have hereunto set my hand in presence of two subscribing witnesses.

JACOB KAST.
